(57) **CLAIM**

The ornamental design for a portion of an audio and charging station for a handheld electronic device, as shown and described.

DESCRIPTION

FIG. 1 is a perspective view of a portion of an audio and charging station for a handheld electronic device showing my new design;

FIG. 2 is a front elevational view thereof;

FIG. 3 is a side elevational view of one side thereof;

FIG. 4 is a side elevational view of the opposite side thereof;

FIG. 5 is a top plan view thereof;

FIG. 6 is a bottom plan view thereof; and,

FIG. 7 is a rear elevational view thereof.

The broken line showings of the two sets of concentric circles on the front face, the feet, the handheld device on top, and the remainder of the audio and charging station are for illustrative purposes only and form no part of the claimed design.
